TOBACCO PIPE

Guy Manley, Danville, Ill.

Application October 16, 1939, Serial No. 299,589

2 Claims. (Cl. 131—186)

This invention relates to a tobacco pipe.

One object of the invention is to provide means of simple and inexpensive construction for supporting a tobacco pipe in an upright position.

5 Another object of the invention is to provide a saliva well which can be cleaned without disassembling the pipe.

Another object of the invention is generally to simplify the construction of tobacco pipes having

10 supporting means and saliva collecting means.

Other objects and features of the invention will be understood from the accompanying drawing and the following description and claims:

Fig. 1 is a side elevational view of a pipe constructed in accordance with the invention. Fig. 2 is a fragmentary central sectional view of one member of the pipe. Fig. 3 is a side view with parts in section of another member. Fig. 4 is an elevational view of a third member of the pipe 20 and Fig. 5 is a sectional view thereof on the line 5—5 of Fig. 4.

In the preferred form of the invention shown in the drawing, the pipe consists of a bowl and stem member 10, a bit member 11 and an auxiliary member 12. The bowl and stem member is in the usual form having a bowl 13 and a partial stem 14 in which there is provided a counterbore 15 and a central smoke conducting bore 16 communicating with the bowl. The bit member 11 is provided with a reduced extension having a portion 17 fitting a bore 18 in the auxiliary member and a further portion 19 fitting the counterbore 15. The bit member has the usual central smoke bore 20. The auxiliary member 12 has a downwardly extending portion 21 adapted to serve as a support for the pipe to maintain the same in an upright position as shown in Fig. 1. Said downwardly extending portion has a central passage 22 adapted to receive a plug 23 of absorbent cotton or other suitable material for collecting saliva. The portion 17 of the bit member has a passage 24 in the underside thereof which establishes communication between the passage 22 and the bore 20

40 of the bit member. A mark 25 on the outside of the bit member indicates, when placed on the left side of the pipe, that the passages 24 and 22 are in communication with each other. When it is desired that there be no such communication, the bit member 11 may be rotated to place the mark 25 on the opposite side.

In the use of the pipe, a plug of absorbent cotton is placed in the passage 22. Said plug receives the greater part of the saliva passing through the bore of the pipe and keeps the bore,

the bowl and the smoking tobacco therein dry. It thus provides an exceptionally clean, dry smoke. At appropriate intervals, the plug may be removed and replaced. At such times the smoker may cover the bowl with the palm of his hand, blow through the bit member and thus clean out any remaining bits of saliva. The bore 16 of the partial stem may then be cleaned with the usual form of pipe stem cleaner without disassembling the pipe. If the plug 23 becomes 10 fouled and the smoker has no replacement immediately available, he may turn the bit member 11 around through 180° and use the pipe as he would any standard form of pipe. The same 15 result may be accomplished more conveniently by turning the auxiliary member since said member usually fits more freely on the bit than does the bowl and stem member and there is less chance of breaking the bit in turning.

The use of the portion 21 in supporting the 20 pipe insures that it may be laid away at any convenient place without danger of spilling ashes or unburned tobacco. The construction by which these results are accomplished is extremely simple and requires no great departure from ordinary pipe making practice. The only additional 25 operation on the two otherwise standard pipe members 10 and 11 is to provide the reduced portion 17 of the bit member. The additional auxiliary member 12 is extremely simple and easily molded. Thus the expense of construction is much less than with other forms of pipes having saliva collecting means or smoke filters and the support of the pipe by the auxiliary member 12 is an additional advantage.

35 The invention has been described in one of its preferred forms. Details may of course be varied without departing from the scope of the invention as defined by the appended claims.

The invention claimed is:

40 1. A tobacco pipe comprising a bowl and stem member, a bit member and an auxiliary member, said bowl and stem member having a counterbore and said auxiliary member having a bore therethrough, said bit member having a reduced extension fitting said bore and extending into and mating with said counterbore, said first two members having a continuous central bore passing through said extension, said auxiliary member having a downwardly extending portion 45 adapted to support the pipe, said downwardly extending portion having a passage open at the bottom, and said reduced extension having a passage establishing communication between said first mentioned passage and said central bore 50

55 adapted to receive a plug of absorbent cotton or other suitable material for collecting saliva.

when said bit member is in a predetermined angular position with relation to said auxiliary member but out of communication therewith when in a different angular position.

- 5 2. A tobacco pipe comprising a bowl and stem member, a bit member and an auxiliary member, said auxiliary member having a bore therethrough, one of said first two members having a counterbore and the other having a reduced 5
10 extension fitting said bore and extending into and mating with said counterbore, said first two members having a continuous central bore passing

through said extension, said auxiliary member having a downwardly extending portion adapted to support the pipe, said downwardly extending portion having a passage open at the bottom, and said reduced extension having a passage establishing communication between said first mentioned passage and said central bore when said extension is in a predetermined angular position with relation to said auxiliary member but out of communication therewith when in a different 10 angular position.
